UNITED STATES PATENT OFFICE

VICTOR G. W. GILBERT, OF LONDON, ENGLAND, ASSIGNOR TO AMERICAN LA FRANCE AND FOAMITE CORPORATION, OF NEW YORK, N. Y., A CORPORATION OF NEW YORK

FIRE-EXTINGUISHING APPARATUS

Application filed April 9, 1928, Serial No. 268,681, and in Great Britain April 22, 1927.

The invention relates to portable fire-extinguishing apparatus of the kind comprising generally a container having two compartments for the component solutions, which may be foam-making solutions, and a common outlet through which the solutions or foam is expelled in time of fire.

The object of the invention is the prevention of accidental spilling of the solutions or premature mixture thereof, as by splashing one into the other, and comprises improved means for closing both the foam outlet and one of the solution compartments. More particularly the invention contemplates the arrangements and mode of operation exemplified by the apparatus shown in the accompanying drawings and as pointed out in the claims.

Fig. 1 is a vertical section of an extinguisher showing a preferred application of the principles of the invention.

Figs. 2 and 3 sectional views respectively on the lines II—II and III—III of Fig. 1,

Fig. 4 an end view of the extinguisher shown in Fig. 1,

Fig. 5 a vertical section of a modified form,

Fig. 6 is a broken section on the line VI—VI of Fig. 5 and

Fig. 7 a section on the line VII—VII of Fig. 1.

The extinguisher illustrated is of the kind adapted to be manually inverted in line of fire to effect the mixture of the solutions and will be recognized as including an outer container 1 and an inner container 2, comprising the solution compartments, closure cap 3, and handles 4 and 5, the latter being conveniently located for holding the extinguisher when inverted.

Referring to Figs. 1—4, the inner container is of annular form and at its upper end is secured to a cage member 6, which may be a casting extending into and fitting the neck 7 of the outer container. A spider 8, preferably formed integrally with the cage, has a hub 9 recessed to fit over the inner wall of the annular container. The hub is apertured, as at 10, forming a shoulder 11 which seats upon a tube 12 secured to and extending upwardly from the bottom of the container 1.

A soft washer 13 of lead or the like, constituting a seal may be inserted between the shoulder 11 and the upper end of the tube. The inner container is thus supported on the tube 12 and can be readily withdrawn when the cap 3 is removed. The upper rim of the cage engages the usual closure cap gasket so that by holding the hub 9 in contact with its seat on the tube 12 the inner container is firmly held in position.

The tube 12 serves as the discharge outlet of the extinguisher and to this end passes through the bottom of the container 1 into a fixed and laterally directed nozzle 14 which may be threaded on the end of the outlet tube and welded or brazed to the bottom of the container. As shown the nozzle is protected at all times by the skirt 15 of the outer container, a hole 16 providing for the passage of the mixed solutions or foam.

The upper face of the spider constitutes a seat for a stopple or valve member 17 which is provided with a soft facing 18 to engage the upstanding shoulders 19 and 20 of the spider. By this single means both the outlet tube 12 and the inner container 2 are closed, thereby preventing splashing of one solution into the other or through the outlet as when the extinguisher is tilted or agitated during transit to the scene of the fire.

In the modified form of Figs. 5, 6 and 7, the neck 7 of the container is formed with a plurality of depending hangers 21, four of which are shown in Fig. 7, which serve as the support for the inner container and also embody a discharge outlet to the nozzle. Each of the hangers has a shoulder 22, one of them being enlarged, as shown at 23 in Figs. 5 and 7. The cage 6 fits the container neck, as above, and is shouldered to provide a seat 24 adapted to engage the shoulders 22 to support the inner container, which, in this case, may be of any usual or suitable form. The cage is held in engagement with its seat by the closure cap and gasket. Preferably, the container 2 is flattened along one side, thereby permitting a wider formation of the seat 24 adjacent the hanger enlargement 23 and also ensuring the proper positioning of the cage with respect to the enlargement, which

is also flattened at this point (Fig. 7). Registering passages 25, 26 in the cage and hanger enlargement constitute the discharge outlet to the nozzle, which in this form is rigidly secured to the side wall of the container and connected with the opening 26 by a short pipe 27 which is seated in an enlargement of passage 26.

The foam outlet is thus brought into proximity to the mouth of the inner container and is therefore capable of control, as above, by means of the valve 17 which serves to close the container 2.

A cup member 28 upstanding from the bottom of the outer container may be provided to receive, and prevent undue lateral movement of, the lower end of the inner container.

In both forms of the invention external valve operating means are shown, comprising a threaded stem 29 passing through a stuffing box carried by the closure cap; on its outer end the stem is provided with a hand wheel 30 and on its inner end with a head 31 loosely enclosed by a yoke 32 upstanding from the back of the valve. When the hand wheel is turned to tighten the valve against its seat, the extinguisher can be tilted, agitated or even inverted without fear of either of the solutions splashing into each other, or of one or the other of them spilling out through the nozzle. In time of fire it is merely necessary to turn the hand-wheel to lift the valve clear of its seat and invert the extinguisher; both the discharge outlet and the inner container being open, the solutions will be mixed and expelled by way of nozzle 14 in the usual manner.

It will also be apparent that by removing the closure cap, the inner container and cage may be withdrawn as a unit. Thereupon immediate access may be had both to the container 1 and the discharge outlet, for inspection or cleaning, and without in any way disturbing the nozzle or outlet connections.

Having now described my invention I claim:

1. A fire extinguisher comprising an outer solution container, an inner solution container having an outlet constituting a valve seat, a discharge nozzle outside of said outer container, a tube within said container connected with the nozzle and terminating in a valve seat, said valve seats being approximately in the same plane, and a single externally-operated valve member simultaneously engageable with both said seats and arranged to close in the direction of flow through said tube.

2. In a fire extinguisher the combination of an inner solution container, an outer container having its side walls extended below the bottom of the same to provide a supporting skirt, an open discharge nozzle located within the space enclosed by said skirt, a foam discharge tube communicating with

said nozzle and extending upwardly within the outer container, a closure cap for the upper end of the latter, a valve adapted to seat on the upper end of said tube and external operating means for the valve carried by the closure cap. 70

3. A fire extinguisher comprising in combination an outer solution container, an inner solution container, a discharge tube arranged to support the latter within the outer container and terminating at its inner end adjacent the mouth of the inner container and an externally operated valve member simultaneously controlling the said end of the discharge tube and the mouth of the inner container. 75

4. A fire extinguisher comprising in combination an outer solution container, a centrally located, longitudinally extending discharge tube, an inner solution container of annular form encircling said tube, the upper end of the inner container and said tube terminating in valve seats arranged approximately in the same plane, and a single valve member adapted to simultaneously engage both said seats. 80

5. A fire extinguisher comprising an outer solution container, an inner solution container, a supporting member for the latter having a foam discharge outlet and adapted to support said inner container with its open end substantially in the plane of said outlet, and a valve operable to simultaneously open or close the outlet and inner container. 85

6. In a fire extinguisher, the combination of an outer solution container having a neck casting, inner container supporting means depending therefrom and having a foam discharge outlet, an inner container adapted to be inserted into and supported by said means with its upper end adjacent said outlet, and a common valve for said outlet and inner container. 100

In testimony whereof, I have signed this specification.

VICTOR G. W. GILBERT.
